(57) **CLAIM**

The ornamental design for a bench chair, as shown and described.

DESCRIPTION

FIG. 1 is a front, right, and top perspective view of a bench chair, showing my new design;

FIG. 2 is a rear, right, and bottom elevation view thereof;

FIG. 3 is a front elevation view thereof;

FIG. 4 is a rear view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of an encircled area labeled "9" in FIG. 1; and,

FIG. 10 is an enlarged view of an encircled area labeled "10" in FIG. 1.

The broken lines shown in the drawings are included for the purpose of illustrating portions of the bench chair that form no part of the claimed design.

Dot-dash broken lines in FIGS. 1 and 9 framing portions of the claimed design that are illustrated for enlargements form no part of the claimed design.

Dot-dash broken lines in FIGS. 1 and 10 framing portions of the claimed design that are illustrated for enlargements form no part of the claimed design.

1 Claim, 10 Drawing Sheets
